Patent expires August 23, 1963

2 Claims. (Cl. 179—171)

1

This invention relates to a circuit-arrangement for the transmission of electric oscillations, particularly of a wide frequency band or of ultra-high frequencies, in which a discharge tube is used which is provided with a secondary emission electrode which also acts as an output electrode and which in the proximity of the secondary emission electrode and in the path of the secondary electrons comprises a grid whose bias is higher than that of the secondary emission electrode.

It is known that in the so-called wide band amplifiers the width of the frequency band to be transmitted is solely determined by the capacity occurring between the output electrode and the cathode; the lower the said capacity, the larger is the frequency band allowed to pass. This remark applies both to circuit-arrangements for the transmission of modulated oscillations (for example high or intermediate frequency amplifiers for television or for frequency-modulated oscillations) and to circuit-arrangements for the transmission of non-modulated oscillations (for example video frequency amplifiers for television). In addition, in amplifiers for ultra-high frequency oscillations the maximum impedance of the output resonant circuit and consequently the achievable amplification are also solely determined by the capacity between output electrode and cathode. It is therefore of paramount importance to take care that this capacity is minimized in circuit-arrangements of the said descriptions.

In the transmission of wide frequency bands and of ultra-high frequencies the amplification to be obtained is generally limited, so that for this purpose use may be made with advantage of the so-called secondary emission tubes, which have a very high mutual conductance. It may, in some cases, be of use to employ the secondary emission electrode also as an output electrode. This measure may be taken, for example, if an amplification without phase shift is desired or if two frequency bands (for example, image and sound frequencies in television) are to be separated; in the latter case the oscillations associated with one of the bands may be taken from the anode and the oscillations associated with the other band from the secondary-emission electrode.

Now, a grid is frequently arranged in secondary emission tubes in the proximity of the secondary-emission electrode and in the path of the secondary electrons, said grid having a higher bias than the secondary-emission electrode, for example the same bias as the anode, and having the

function of drawing away the secondary electrons from the secondary-emission electrode. This grid is generally connected direct to the anode inside the tube; it has, however, also been suggested before to provide the grid concerned with a separate supply lead. In the use of such tubes in circuit-arrangements for the transmission of a wide frequency band or of ultra-high frequencies, there is the disadvantage that the capacity between the secondary emission electrode and the cathode is comparatively high, so that the secondary emission electrode cannot be utilized without difficulty as an output electrode.

The invention has for its object to obviate this disadvantage. According to the invention, to this end a high impedance for the oscillations to be transmitted is provided between the said grid and the source of direct voltage which supplies the bias for this grid.

20 The said grid is preferably connected to the source of direct voltage through a high-ohmic resistance. For this purpose the said resistance may be arranged, for example, inside the tube between the said grid and the anode.

25 In order that the invention may be clearly understood and readily carried into effect, it will now be explained more fully with reference to the accompanying drawing, in which one form of construction is illustrated.

30 On the drawing is shown an amplifier for a wide frequency band comprising a discharge tube 1 which is provided with a cathode 2, a control grid 3, a screen grid 4, a secondary emission electrode 5, a grid 6 arranged in the path of the secondary electrons and an anode 7. The oscillations to be amplified are supplied to the control grid 3 through terminals 8 and 9. The circuit of the secondary emission electrode includes a resistance 10, from which the amplified oscillations are obtained through terminals 11 and 12. The anode 7 is connected to earth, via a condenser 13, for the frequencies of the oscillations to be amplified. A resistance 14 shunted by a condenser is included in the cathode lead in the usual manner for the generation of the control grid bias.

45 According to the invention, the grid 6 is connected to the anode 7 through a high-ohmic resistance 15. The effect of this measure may be explained as follows.

50 In the usual circuit-arrangements the grid 6 was connected direct to the anode 7, the capacity between the secondary-emission electrode and earth being primarily constituted by the capacity C_1 between the secondary-emission electrode and the anode and by the capacity C_2 between the

secondary-emission electrode and the grid 6 and being consequently $C_1 + C_2$; the other capacities between the secondary-emission electrode and earth (for example, the parasitic capacity of the resistance 10 and the capacity between the secondary-emission electrode and the screen grid 4) may be assumed to be included in the capacity C_1 .

In the circuit-arrangement according to the invention the grid 6 is practically insulated with respect to earth by the high impedance included in the circuit of this grid, so that for the capacity between the secondary emission electrode and the grid 6 is substituted the series combination of this capacity and the capacity C_3 between the grid 6 and the anode 7. Thus, the total capacity between the secondary-emission electrode and earth is

$$C_1 + \frac{C_2 \cdot C_3}{C_2 + C_3}$$

and is consequently lower than in the usual circuit-arrangements. A considerable reduction (for example of several pfs.) of the total output capacitive reactions is obtainable in practice by the use of the invention.

In order to avoid an increase of the output capacity by the capacity of the supply lead of the grid 6 with respect to the anode and the secondary-emission electrode the resistance 15 is preferably arranged inside the tube between the grid 6 and the anode. The resistance 15 may, in practice, have a value of several megohms. The invention may also be used with advantage in circuit-arrangements in which the tube 1 is provided with a photo-electric cathode instead of the cathode 2 and the control grid 3.

What I claim is:

1. An electric wave transmission circuit comprising a thermionic discharge tube having a cathode, anode, secondary emissive electrode and a grid included in the electron path between said anode and secondary electrode, a source of de-

sired signals, means to modulate the electron path of the said thermionic discharge tube in accordance with said signals, a first source of direct current potential of given voltage, an output stage, means to couple said first source of potential and said output stage to the secondary emissive electrode-cathode circuit of said thermionic discharge tube, a resistive element, means to connect said resistive element between said grid and the anode of the said thermionic discharge tube, a second source of direct current potential having a higher voltage than the first source of potential, and means to connect said second source of potential to the anode of said thermionic discharge tube.

2. An electric wave transmission circuit comprising a thermionic discharge tube having a cathode, anode, secondary emissive electrode and a grid included in the electron path between said anode and secondary electrode, a resistive element connected internally in said thermionic discharge tube between the anode and the grid, a first source of direct current potential of given voltage, an output stage, means to couple said first source of potential and said output stage to the secondary emissive electrode-cathode circuit of said thermionic discharge tube, a second source of direct current potential having a higher voltage than the first source of potential, and means to connect said second source of potential to the anode of said thermionic discharge tube.
